UNITED STATES PATENT OFFICE

HENRY ZIEMMERMAN, OF CHICAGO, ILLINOIS, ASSIGNOR TO CHICAGO CARDBOARD COMPANY, OF CHICAGO, ILLINOIS, A CORPORATION OF ILLINOIS

FOLDING DISPLAY

Application filed July 11, 1930. Serial No. 467,174.

This invention relates in general to a folding display particularly for advertising and has more particular reference to a cardboard display device which is made up of folding 5 parts located in different planes.

One of the principal objects of the invention is in the provision of a folding display in which the parts are so proportioned, scored, cut and folded that a full sized 10 vice can be collapsed into a relatively small space for shipping and storage without damaging any of the parts.

A further object of the invention is in the provision of a folding display device in 15 which the display planes are located, when extended in relatively spaced apart condition, but which when folded will be in flat superposed position so that a number of such devices can be piled or placed one upon the 20 other without damaging any of the parts.

A further object of the invention is in the provision of cuts and score lines in a display device of this kind which will enable it to fold compactly without breaking the folding 25 joints.

Other objects of the invention will appear hereinafter, a preferred embodiment of the invention being illustrated in the accompanying drawings.

30 In the drawings, Figure 1 is a front perspective of a display device embodying the features of this invention;

Figure 2 is a rear perspective of the display shown in Figure 1;

35 Figure 3 is a perspective of the rear of the display with the back plane folded against the front one;

Figure 4 is a perspective of the display when partially folded with the upper end 40 turned over on the lower one;

Figure 5 is a section taken on the line 5—5 of Figure 2;

Figure 6 is a section taken on the line 6—6 of Figure 3;

45 Figure 7 is a top view of the folded display

as taken upon the line 7—7 of Figure 4; Figure 8 is a detail section taken on the line 8—8 of Figure 2;

Figure 9 is an enlarged detail taken on the line 9—9 of Figure 3; and

50 Figure 10 is an enlarged detail taken on the line 10—10 of Figure 4.

One of the difficulties in collapsing a folding display stand which is made up of several pieces secured together, is that at any 55 place where a number of thickness of the material must be folded upon themselves, the material is sure to break, and thus to throw the parts out of alinement, to destroy the connections between the parts, and to make 60 the structure inoperative after being set up and folded a few times.

The present invention proposes to overcome these objections by so designing a display stand that the fold lines of various members constituting the structure will be located 65 upon the same line, the separations of certain sections which would necessarily be made after the parts were folded upon themselves are made in the proper places in advance, and in addition provision is made for permitting a 70 flexing of the parts which allows them to bend out of the plane in which they are located when the device is extended.

75 Referring more particularly to the drawings, a front plane 11 of cardboard or the like in the form of a frame open at the center with a transverse folding score line 11^a has attached to it at the rear a second sheet 12 of material which forms a box-like structure when extended, as shown in Figure 2. The edges 13 of this second sheet are attached at the sides of the frame 11 and the second sheet is scored at the corners to fold 80 from a rectangular box-like position, as shown more clearly in Figure 5, to a flat position as shown in Figure 6. At the top is a lid 14 formed with perforations 15 for engaging tongues 16 to hold the back sheet in 85 distended position, as shown more clearly 90

in Figures 2 and 8. At the bottom are extensions 17 forming feet to assist in supporting the display device in its extended position.

5 The first collapsing action of the back sheet against the front sheet is relatively simple but the difficult problem is to again fold these sections upon themselves without breaking the folding joints.

10 In the present invention this is accomplished by providing slits 18 and 19 extending transversely of the horizontal or intermediate fold line 20 of the rear sheet 12, these slits 18 and 19 being so located that 15 when the sections are folded over upon each other, as shown in Figure 4, the slits will be located between the sides of the frame 11 and that part 20^a of the fold line 20 which is outside of the portion between the slits 18 20 and 19 is actually cut so that the parts of the back sheet 12 when folded, as shown in Figure 4, will be actually separated. This prevents the breaking of the joint and holds the upper and lower sections of the rear sheet 25 together and in proper alinement with respect to each other.

For the purpose of further strengthening the parts and preventing the upper and lower sections from disengaging, a number 30 of hinges 21 and 22 are secured to the rear faces of the front and back sheets 11 and 12, these hinges being formed of a fabric and pasted to the upper and lower sections with a small loop 23 at the fold line which will 35 allow the sheets to fold over forwardly against each other and still make a tight connection at the hinge in this position, as shown more clearly by Figures 9 and 10.

By locating the transverse slits 18 and 19 40 in this manner, the sheets may be folded upon each other as the slits in the fold line itself will permit the upper and lower sections of the rear sheet to separate in folding but still the connection between the upper 45 and lower sections of the rear sheet will hold the parts in alinement and will present an unbroken surface at the front, both of the front plate 11 and the major exposed portion of the rear sheet 12. The slits 18 and 50 19 are practically invisible from the front of a display device, the slits 20 are at the rear of the front plate 11 and when the front and rear sheets are additionally covered with printing, coloring and other advertising or 55 display material, the fold lines and the slits are practically invisible and certainly are unobjectionable as they are not easily discovered. By having the sections attached in this manner, the display is easily set up 60 and folded, it is not likely that the fold lines will be broken, and it is practically impossible to make a mistake in unfolding or collapsing the parts.

I claim:

65 1. A display device comprising cardboard

sheets attached together at the edges and one at the back of the other with transverse score lines adapting them to fold over together, a portion of the score line of one of the sheets being completely severed to allow the remaining folded portions of both sheets to assume the same straight line of folding.

2. A folding display device comprising cardboard or similar sheets attached together at the edges one at the back of the other and provided with corresponding transverse fold lines adapting the sheets to fold over upon each other, the fold line of one of the sheets being completely severed for a portion of the way to permit the sheets to fold over upon each other in a single thickness without breaking the score lines.

3. In a folding display, a plurality of sheets secured together one at the back of the other and collapsible one upon the other, the sheets being provided with transverse score lines adapting them to fold over upon each other and the score line of one of the sheets having a transverse slit beyond which the score line is cut entirely through the sheet.

4. In a folding display, the combination with a front plate having a central opening with side portions and foldable forwardly upon itself, of a rear plate having sides attached to the side portions and the intermediate portion spaced from the front plate when unfolded but collapsible against the back of the front plate, the rear plate being scored for folding between the side portions and the fold lines thereof back of the side portions being cut through for separation of the parts when the rear plate is collapsed and folded together with the front plate.

5. In a folding display, a pair of plates secured together at the edges one at the back of the other and scored for collapsing one against the other and folding both plates together, one of the plates having an aperture into which the folded portion of the other extends in folding, and the score lines of the other being cut through for separation in the portions which do not extend into the aperture.

6. In a folding display, the combination of two cardboard plates secured together at spaced distances and foldable together for compactness, and unfolding to space one at a distance from the other, one of the plates being first foldable to collapse against the other and the collapsing folds being cut through transversely to separate the parts thereof when the two plates are folded together for compactness.

7. In a folding display, the combination of two cardboard plates secured together at the edges and one disposed at the back of the other and scored for collapsing and unfolding with respect to the other, the front plate having a central aperture through which the

other plate is visible, and the two plates being scored transversely to fold forwardly placing the front surfaces of the front plate together, the transverse score line of the rear 5 plate being cut entirely through at the edges so that the collapsing folds thereof will be cut through and separated where the two plates are folded forwardly together, the fold lines of the sides of the front plate and the 10 central portion of the rear plate coinciding in a straight line when the display is folded.
